ATTORNEY.

UNITED STATES PATENT OFFICE

PETER J. McCORMICK, OF HAGERSTOWN, MARYLAND

WASHING MACHINE

Application filed November 2, 1928. Serial No. 316,865.

My invention relates to a washing machine adapted to permit water and suds to be scooped up to pass through the wall of a drum or rotating cylinder and preferably 5 in tangential or substantially tangential direction thereof.

For this purpose I provide the drum, which is made to revolve in one direction, only with a series of peripheral buckets or 10 scoops all facing in the same direction, that is to say, in the direction of rotation of the drum, thereby forcing the washing liquid from the outside into the drum and through the fabric of the clothes contained therein. 15 This has the advantage of exposing the material to be washed to a very thorough circulation of washing solution, hot or cold, thus avoiding the usual pounding, wringing, or squeezing of the material, which operations are very detrimental to the same— 20 causing its quick wearing out or total destruction.

Some of the objects and advantages 25 claimed for this invention will here be enumerated:

The construction of my washing machine is very simple, as it consists of very few parts and has, as a consequence, a very low cost of manufacture.

30 Due to the absence of vibrations the life of the apparatus is considerably longer than with ordinary washing machines in which the constant reversal of motion causes a violent shaking of all parts of the machine and 35 early disintegration and breaking up of its metallic structure. This has also for effect that the washing becomes less thorough, because no sooner is the washing solution about to enter from one side of the fabric 40 than its direction is abruptly reversed, so that only the outer surface of the fabric will be washed. With the uniform running in the same direction of the apparatus forming the subject matter of the present invention, 45 on the other hand, the washing solution is forced right through the fabric and in one direction only, so that not only the surfaces but also the interior of the fabric becomes 50 cleansed. For the same reason and the absence 55 of the jerking back and forth of the

moving parts, the machine itself will last much longer.

By embodying this principle of forcing the cleansing fluid through the fabric, all foreign substances are quickly and easily 55 removed, and a much shorter time is required for completely cleaning a garment.

On account of no reversing of the machine being made and its constantly revolving in the same direction, the operation 60 becomes practically noiseless and the power consumption and cost of operation is greatly reduced.

In the accompanying drawings one embodiment of the invention is illustrated, 65 and:

Figure 1 is a perspective view of the washing machine forming the subject matter of the present invention.

Figure 2 is a transverse section of Figure 70 3.

Figure 3 is a vertical section along line 3—3 of Figure 2 with the drum in partial elevation and section.

Figure 4 is a vertical section in larger 75 scale of a detail of the apparatus; and,

Figure 5 is a face view of Figure 4.

Like references in the several figures of the drawings refer to the same parts of the apparatus.

Reference numeral 10 represents the container or housing with a dome-like or semi-cylindrical top portion 11 provided with a hopper or mouth portion 12 through which the material to be washed is deposited in the washing machine. The bottom 9 is preferably made in the form of a half cylinder. 80

The two flat end walls 13 are provided with bearings 14 for stub-shafts 15 and 16 of which the latter carries a crank 17 in case the machine is hand operated. In case the machine is to be power driven a pulley may take the place of the crank or the shaft 16 may be directly connected to a small electric motor or the like. Roller 30 95 may be provided under the container and a drain cock 8 in one end thereof.

Each of the stub-shafts 15 and 16 is of spider shape, that is to say, a plurality of radial arms 18 extend from its hub portion 100

19 to the mantle 20 of the drum 21 to which they are suitably secured as by bolts or rivets 22 that pass through said mantle and the inturned end portions of the arms 18 as shown in Figure 3. The end walls 23 of the drum are preferably formed of wire screen but it is evident that these walls may be made of perforated sheets to permit circulation of liquid in case other material is used. These end walls are in suitable manner secured to the mantle 20 and the arms 18.

15 The mantle 20 is provided with a door 27 curved to conform to the cylindrical shape of the mantle and secured in position by the usual hinges 28 and latch or clasp 29.

20 In staggered rows on the mantle are to be found a series of exteriorly opening buckets or scoops 24 and in circumferential alignment therewith similar buckets 25 opening inwards of the mantle. The main or exterior buckets 24 are facing in the direction of rotation of the drum, so that with the latter revolving as indicated by arrow X the washing solution will be scooped up by these exterior buckets to enter the drum to circulate therein. The shape and formation of the buckets is best seen in Figures 4 and 5 of the drawings. They are pressed or stamped when preparing the plate for the mantle after first making a slit 26 which will form the forward edge or lip of the exterior bucket 24 and the rearward edge of the interior bucket or pocket 25. In other words the material forming each exterior bucket bulges outwardly while that of the interior bucket bulges in so that the adjacent edges of a pair of buckets 24, 25 together describe a circle. In this manner comparatively wide openings around the periphery of the drum are furnished through which the liquid readily enters the drum when it rotates in the housing in the direction denoted by arrow X. Accordingly, during 45 operation the washing solution always enters the drum through the buckets 24, always proceeding in one direction and leaves the drum through the screened or perforated ends 23. In this manner the washing medium is compelled to pass completely through the fabric contained in the drum, thereby performing a very thorough cleaning. The novel construction of apertures 26, i. e., the outwardly and inwardly 50 bulges, give openings of maximum area at right angles to tangents and thereby permit of easy and forceful in-take flow of water when the clothes container is rotated and thereby the greatest efficiency of the machine is obtained. A further advantage in this formation of water scoops or intakes is that the clothes containing drum of the machine may be manufactured at a lesser cost than where the water apertures 55 are of a more complicated design.

Instead of making an all-metal drum as described above it may in some cases be preferable to use other material such as porcelain, glass, or fiber, in which case the construction of the drum will naturally follow different lines.

10 The operation of the machine is as follows:

15 The drum 21 is first turned until it takes the position indicated in Figures 2 and 3 with the door 27 uppermost so as to register with the hopper opening 12. The door 27 is next opened and the material to be washed deposited in the drum, whereupon the door is closed and secured by the latch 29. At 20 this time, or previous to placing the clothes in the drum, the water and suds are poured into the container or housing 10, whereupon the drum is started to revolve always in the direction of arrow X and never reversely. 25 As already stated the drum may be either hand or power operated.

20 After running a sufficient length of time, the washing solution may be drained out of the machine and clean water substituted for rinsing the clothes during continued revolving of the drum. If now the container is again drained, the moisture may be removed from the clothes by increasing the speed of rotating the drum. Finally, the 25 latter is stopped with the door uppermost, so that it may be opened and the clothes removed.

25 It will be noted the machine is of such simple construction that the same may be manufactured from practically ordinary stock purchased in the open market and thereby produced in large quantities at small cost. That is to say, the design and construction of the machine are such that there will be no necessity for making special parts which in this particular art would increase the cost of making to a point that would otherwise render the manufacture and sale thereof prohibitive.

30 It is to be understood that the invention is not limited to the details of construction here shown and described, but that these may be varied widely without departing from the spirit of the invention as defined by the claim.

35 What I claim as new is:

40 A washing machine comprising a vessel, a cylindrical clothes container journaled in said vessel and providing therewith a constricted annular space for the washing solution; said container comprising two stub-shafts journaled in the sides of the vessel, spider arms mounted on said stub-shafts and having inturned end portion, screen sections 45 overlying said arms and providing water passageways, and a sheet metal drum fitting within the inturned ends of and connecting said spider arms and therewith providing the clothes container, said drum having a 50

plurality of apertures, each of said apertures being formed by outwardly and inwardly metal expanded portions, said portions being immediately adjacent and oppositely disposed providing orifices for scooping-in water when the container is rotated, substantially as set forth.

In witness whereof, I have hereunto set my hand at Washington, D. C., this eleventh day of October, A. D. nineteen hundred and twenty-eight.

PETER J. McCORMICK.
